UNITED STATES PATENT OFFICE.

VICTOR C. ARMSTRONG, OF HACKENSACK, NEW JERSEY, ASSIGNOR TO THE RAIL JOINT COMPANY, OF NEW YORK, N. Y., A CORPORATION OF NEW YORK.

INSULATED RAIL-JOINT.

1,183,335.

Specification of Letters Patent.

Patented May 16, 1916.

Application filed November 30, 1914. Serial No. 874,874.

To all whom it may concern:

Be it known that I, VICTOR C. ARMSTRONG, a citizen of the United States, residing at Hackensack, in the county of Bergen and State of New Jersey, have invented certain new and useful Improvements in Insulated Rail-Joints, of which the following is a specification.

This invention relates to insulated rail joints particularly of the type characterized by a steel shoe angle, and wooden or equivalent filler blocks fitting the fishing spaces.

The type of rail joint referred to is exemplified by the well known "Weber" insulated rail joint, in which the upright member of the shoe angle constitutes a bolting plate for the outside of the joint. At the inside side of this style of joint is employed a metal bolting strap which assists to hold together the joint parts, but has no supporting function to assist in holding the base plate up against the bases of the rails. As a consequence of such construction, the rail ends, under traffic, are susceptible of some movement vertically and independently of the base plate of the shoe angle, and, under lateral thrust or similar forces, it is therefore possible for the rail ends to be deflected laterally in an outward direction. The effect of such deflection is to lift the rail bases off of the inner free edge portion of the base plate of the shoe angle. This causes straining and weakening of the various parts of the joint, and also creates a destructive force which cuts and mashes out the base insulation plate. The latter condition prevails on account of the chafing and pounding of the rail bases on the base insulation as the rails rise and fall.

Accordingly, the primary object of the present invention is to provide an insulated rail joint which fully preserves the established valuable and practical features of the Weber insulated rail joint, while at the same time supplementing these features by an improvement which contributes a more substantial and firmer base support for the rail ends, combined with an effective organization of the joint parts so that the same will be compactly and firmly held to the rails.

Preferable practical embodiments of the invention are shown in the accompanying drawings, in which:

Figure 1 is a top plan view of an insulated

rail joint embodying the present invention. Fig. 2 is a cross sectional view on the line 2-2 of Fig. 1. Fig. 3 is a top plan view of a modified design of rail joint constructed in accordance with the present invention. Fig. 4 is a cross sectional view on the line 4-4 of Fig. 3. Fig. 5 is a cross sectional view on the line 5-5 of Fig. 3.

Similar reference characters designate corresponding parts in the several figures of the drawings.

In carrying forward the invention, no change or alteration is required in the standard features of the Weber insulated type of rail joint. These are maintained, both structurally and functionally, so for purposes of illustration, there is shown in the drawings an embodiment of my invention incorporated in such a joint; it being seen from the drawings, that the metal shoe angle A, the insulating shoe angle B, and the wooden or equivalent filler members C are of the same construction and occupy the same relative positions as in the usual form of Weber insulated rail joint. In addition to these conventional features of a joint of this type, the distinctive feature of the present invention resides in the employment of what may be termed a supplemental steel shoe angle 1, which corresponds in its angular form to that of the main shoe angle, and comprises a horizontal base member 2 and an upright bolting girder 3 arising from one edge of said base member and integrally or rigidly united therewith.

The important consideration of the present invention is to arrange the supplemental rail-supporting shoe-angle 1 in such a manner as to secure the novel and useful results referred to. It will be observed that the supplemental shoe angle 1, while disposed within the main shoe angle A, is disposed in an opposite relation thereto, so that its upright bolting girder member 3 is located at the opposite side of the rails from the upright member of the main shoe angle, and hence lies at the inside of the joint. In this position, the horizontal base member 2 of the supplemental shoe angle performs a definite rail-seating and rail supporting function, inasmuch as the rails are seated directly thereon and it occupies a position between the rail bases and the upper side of the base section of the insulating shoe angle B.

The supplemental shoe angle not only provides a supporting base and seat for the rails, but the upright girder or bolting member 3 thereof receives the joint bolts 4 and 5 and clamps against the filler block at the inside of the joint. The joint bolts 4 also extend through the rails, the filler blocks at both sides of the rails, and through the upright member of the main shoe angle located at 10 the outside of the joint. It will thus be seen that the upright girder or member 3 of the supplemental shoe angle performs the desirable function of directly receiving the joint bolts so as to provide, in effect, a rigid 15 supporting connection between the bolts and the inner rail-supporting base member 2, with the result of improving the general efficiency and durability of the joint.

To provide means for completing the insulation of a joint of the character described, it is usual to employ outer bolting straps 5 at the outside of the joint for the nuts of the bolts to bind against, and to interpose insulating strips 6 between such straps and 25 the outer face of the upright member of the main shoe angle. Also, it is necessary, in this form of construction, to divide the supplemental shoe angle into two parts with a sufficient separation between the said parts 30 at the center of the joint, as at 7. The conventional end post insulation may be extended into this separating space between the two parts or sections of the supplemental shoe angle. In connection with the insulating expedients for the joint described, it 35 is to be noted that it is not necessary to provide insulating washers under the bolt heads, because these heads can be clamped directly against the bolting girder or member 3 of 40 the supplemental shoe angle. This is a desirable feature of construction since it effects an economy in the use of insulation, and permits the employment of the conventional button head bolts with oval necks, 45 fitting in correspondingly shaped openings to prevent turning of the bolts.

A further novel and practical embodiment of the invention is illustrated in Figs. 3, 4 and 5 of the drawings, wherein the supplemental rail supporting shoe angle is shown to be of a modified design. This modification essentially involves the use of a supplemental shoe angle designated by the number 8 which is also disposed within the 55 main shoe angle and has its upright bolting girder 9 disposed at the inside of the joint opposite the corresponding member of the main shoe angle which is disposed at the outside of the joint. But, in the modified design 60 sign of supplemental shoe angle, the upright bolting girder or member 9 thereof extends uninterruptedly the full length of the joint, while its horizontal rail supporting base member 10 is of a length approximately 65 equaling only one-half the length of the

joint, and therefore underlies only one rail end M. This construction is produced by shearing off one-half of the base portion of the shoe angle section 8 near the center of the joint as indicated at 11 in Fig. 3 of the drawings. In the modified construction referred to, it will therefore be seen that while the base member of the supplemental shoe angle provides a seat and support for one rail end only, the supporting and holding-up effect of the upright girder or member 9 is maintained to a large degree by extending such girder the entire length of the joint so that it will act as a bolting strap for both rail ends. With this construction, however, it is necessary to place a riser plate 12 beneath the other rail end N. This riser plate is preferably made of insulating material to insure a thorough and effective insulation of the joint, and is held in position by means of insulating rivets 12a or other equivalent and practical fastening means. Also, in this form of construction, in view of the metallic contact between the base members of both shoe angles, it is necessary to thoroughly insulate all of the joint bolts. This is accomplished by insulating the bolt ends at the outside of the joint in the manner already described, and by insulating the bolt ends at the inside of the joint by the use of juxtaposed metal and insulating straps 13-14 interposed between the bolt heads and the bolting girder member of the supplemental shoe angle.

Other desirable and practical modifications of the invention may be resorted to without departing from the distinctive feature thereof which is characterized by the employment of a supplemental steel shoe angle disposed within the main shoe angle and having its upright girder or member disposed at the inside of the joint and receiving the joint bolts to obtain the supporting effect of such bolts, thereby obviating the difficulties and objections met with in the conventional form of Weber type of rail joint having merely bolting straps at the inside of the joint.

I claim:

1. An insulated rail joint including the rails, a main shoe angle extending the full length of the joint, outer and inner filler members, and a supplemental shoe angle disposed within the main shoe angle and clamped against the inner filler, said supplemental shoe angle having a base member extending substantially half the length of the joint.

2. An insulated rail joint including the rails, a main shoe angle extending the full length of the joint, outer and inner filler members, and a supplemental shoe angle disposed within the main shoe angle and having an upright bolting girder clamped against the inner filler, said supplemental

shoe angle extending substantially half the length of the joint.

3. An insulated rail joint including the rails, a main shoe angle extending the full length of the joint, outer and inner filler members, and a supplemental shoe angle disposed within the main shoe angle in reversed relation thereto and provided with an upright bolting girder extending the full length of the joint and clamped against the inner filler, said supplemental shoe angle also having a base member extending substantially half the length of the joint, and a riser complementally related to said base member.

4. An insulated rail joint including the rails, a main shoe angle, a supplemental shoe angle disposed within the main shoe angle in opposite relation thereto and provided with an upright member extending the full

length of the joint, and a base member for one rail end, and a riser plate complementally related to said base member and disposed beneath the other rail end.

5. An insulated rail joint including the rails, joint bolts, and outer and inner fillers, a main shoe angle engaging the outer filler, a supplemental shoe angle disposed within the main shoe angle and engaging the inner filler, said supplemental shoe angle having an upright bolting girder extending the full length of the joint, and a base member for one rail end, and a riser plate disposed beneath the other rail end.

In testimony whereof I hereunto affix my signature in the presence of two witnesses.

VICTOR C. ARMSTRONG.
